UNITED STATES PATENT OFFICE.

JAMES A. MUZZIO, OF CLEVELAND, OHIO.

LOCKING MECHANISM.

Application filed May 25, 1923. Serial No. 641,392.

To all whom it may concern:

Be it known that I, JAMES A. MUZZIO, a citizen of the United States, residing at Cleveland, in the county of Cuyahoga and 5 State of Ohio, have invented certain new and useful Improvements in Locking Mechanism, of which the following is a specification.

This invention relates to locks.

10 The object of the invention is to provide improved locking mechanism including a locking device or strike adapted for attachment to one of the members to be secured together and cooperating with locking mechanism on the other member, said locking mechanism including a plurality of levers or lever members moving in different planes to engage with or be disengaged from the strike, thereby very materially reducing, if 15 not entirely preventing, any liability of tampering with or opening the lock by knocking or vibrating it to free the locking levers from the strike.

Other objects of the invention will be 20 more apparent from the detailed description hereinafter.

In the drawings, Fig. 1 is a front view of locking mechanism embodying the invention; Fig. 2 is a sectional view on the line 2—2, Fig. 3, looking in the direction of the arrows; Fig. 3 is a sectional view on line 3—3, Fig. 2; Fig. 4 is a sectional view on the line 4—4, Fig. 2, showing the lock closed; Fig. 5 is a similar view showing the lock 25 released; and Figs. 6 and 7 are views corresponding to Figs. 4 and 5 and illustrating a modification.

In the drawings, 1 and 2 represent the two parts to be secured together, each thereof 30 carrying a part of the locking mechanism forming the subject matter of this invention. They may be any suitable parts, for example, the lid and receptacle portion of a box, such as a cash box or like article. 45 To the lid 1 is attached a suitable strike member, such as the plate 3 carrying a tongue 4 adapted to enter the lock casing, said tongue having two edge recesses 5 and a through opening 6 to receive the locking 50 levers as will appear. It may also be recessed as at 7 to avoid interference with the rotatable plug.

To the inside of member 2 is secured the lock casing, represented generally at 8, and 55 formed of any suitable material and of any size and shape as will be obvious. To one

wall of the casing are pivotally connected at 9 a pair of locking levers 10 adapted to turn in the same plane and having hooked end portions 11 disposed on opposite sides of 60 the strike and adapted to enter the recesses 5 thereof. The strike engaging ends of said levers are yieldably urged toward each other by a suitable spring 12. Said levers swing in a plane transverse to the axis of the key 65 controlled locking device which may be of any suitable form and, as shown, comprises plug and barrel members 13, 14, the latter suitably secured to the casing and the former adapted to receive a key by which 70 it may be rotated in the barrel, as is usual. The rear end of said plug, or a part attached thereto, marked 15, is of cylindrical form except where it is flattened off on two opposing sides, as at 16, and lies between the 75 oppositely disposed levers 10. This plug member 15 serves as a cam adapted by rotation of the plug to either separate the levers 10 or allow them to close. Rotatable motion 80 of the plug may be limited if desired by suitable means, such as the pin 17 cooperating with one of the flat faces of member 15.

Since the two levers 10 swing or oscillate in the same plane it is possible for a skilled 85 unauthorized person not possessing a key to open the lock by vibration or blows imparted to the mechanism or the device to which it is attached in the direction of said plane. Such blows or vibration may possibly jar the levers out of locking engagement with the strike. I therefore provide 90 this locking mechanism with additional means engaging the strike and movable in a different plane from said levers. Such 95 means may be of any suitable form so long as it is yieldable or self locking or engaging in character and may be operated by rotation of the plug 13. Figs. 6 and 7 show for 100 this purpose a lever member 18 pivoted at 19 in a suitable bracket on the casing and formed of twisted or bent sheet metal. Said lever is backed by a light spring 20, the effect of which is to urge the lever 18 forwardly and cause its hooked locking end portion 21 to enter the recess 6 in the strike 105 which is bevelled off at 7 for the automatic locking engagement found in structures of this character. Figs. 1 to 5 inclusive, show 110 the preferred form, in which the lever is a metal bar 18^a of springy or resilient material riveted or otherwise rigidly secured

at 22 to the casing. The resiliency of this member normally urges it into locking engagement with the strike in the same manner as the effect of spring 20 upon lever 18. Both forms of lever are the same in so far as they are actuated by the rotatable lock plug, the rear end of which has a portion bevelled off laterally, as at 23, to form a cam portion which lies opposite a bent or inclined portion 24 of the locking lever, as shown in Fig. 3. Figs. 3, 4 and 6 represent the locked position of the parts. If the key is inserted and the lock plug turned the effect of the cam 23 upon the bevelled portion 24 of the lever is to push the same back against its inherent resiliency or the effect of the spring 20 into a cavity 25 of the casing; thereby freeing said lever of engagement with the strike at the same time that the levers 10 are released therefrom.

With both forms of the invention the strike automatically opens all three locking levers and can be moved to locking engagement therewith without the presence of a key. Rotation of the same plug releases all three levers, even though they move in three different directions from the rotatable plug. At the same time the construction is simple and is not likely to get out of order.

30 What I claim is:

1. Locking mechanism, comprising relatively rotatable cylinder and plug members, and locking levers actuated by the rotatable member, one of said levers moving in a plane transverse to the plug axis and the other in a plane parallel therewith. 35

2. Locking mechanism, comprising relatively rotatable cylinder and plug members, a pair of locking levers oppositely movable in a plane transverse to the plug axis, and a third locking lever opposite the end of the 40 plug and movable in a plane parallel with its axis.

3. Locking mechanism, comprising a cylinder, a plug rotatable therein, locking levers movable transversely to and parallel 45 with the plug axis, and means actuated by the plug for operating said levers.

4. Locking mechanism, comprising a cylinder, a plug rotatable therein, a pair of locking levers at one end of said plug and 50 movable in a plane transversely thereof, a third locking lever opposite the end of the plug and movable parallel to its axis, and cam means on the side and end of said plug 55 for actuating said levers.

In testimony whereof I hereby affix my signature.

JAMES A. MUZZIO.
